[57] **CLAIM**

The ornamental design for a light fixture, or similar article, as shown and described.

DESCRIPTION

FIG. 1 is a front perspective view of a light fixture, or similar article, showing my new design;

FIG. 2 is a side elevational view thereof on an enlarged scale;

FIG. 3 is a bottom plan view thereof on an enlarged scale; and

FIG. 4 is a top plan view thereof on an enlarged scale. The cross-hatching on the bottom of the fixture is partially shown for convenience of illustration, it being understood that the cross-hatching is uniformly continuous over the area on which it appears.
